UNITED STATES PATENT OFFICE

100,912

DESIGN FOR AN ENSEMBLE DRESS

Joseph Anderman, New York, N. Y.

Application November 2, 1935, Serial No. 59,332

Term of patent 3½ years

To all whom it may concern:

Be it known that I, Joseph Anderman, a citizen of the United States, and a resident of the city of New York, Borough of Bronx, county of Bronx, and State of New York, have invented the new, original, and ornamental Design for an Ensemble Dress, of which the following is a specification, reference being had to the accompanying drawing, forming part thereof, in which

I claim:

The ornamental design for an ensemble dress as shown and described.

JOSEPH ANDERMAN.
